UNITED STATES PATENT OFFICE.

GEORGE J. HAUSMAN AND ALBERT J. JONES, OF CINCINNATI, OHIO.

SHIFTER FOR BELTS ON CONE PULLEYS.

Application filed July 22, 1920. Serial No. 398,121.

To all whom it may concern:

Be it known that we, GEORGE J. HAUSMAN and ALBERT J. JONES, citizens of the United States, residing at Cincinnati, in the county of Hamilton and State of Ohio, have invented certain new and useful Improvements in Shifters for Belts on Cone Pulleys, of which the following is a specification.

Our invention relates to belt-shifters, and its object is to provide for quick and effective shifting of a belt from one set of steps to any other of a pair of cone-pulleys, such as are used on lathes and other machinery where variations of speed are to be made frequently. A further object is to make such a device very simple, and comparatively inexpensive in first cost, easy to install and operate and keep in order, and which will be compact, whereby it may be within very easy reach of the machine operator, yet not be an obstruction or hindrance in the ordinary operation of the machine. Other objects will appear in the course of the ensuing description.

We attain these objects by the device illustrated, for example, in the accompanying drawings, in which—

Figure 1 is a front elevation of part of a machine and its counter-shaft and the cone-pulleys thereon, with our invention, as we prefer to construct it, applied thereto, the device being at a completed stage of belt-shifting operation;

Fig. 2 is a plan view of the same;

Fig. 3 is a detail perspective view of the head with the handle and its lifters mounted thereon;

Fig. 4 is a partial perspective view, enlarged, of the head and parts of the lower bar and lower rack, at an intermediate stage of belt-shifting operation, parts of the head being represented as broken away, to reveal the interior details;

Fig. 5 is a plan view corresponding to Fig. 4;

Fig. 6 is a front elevation of the same;

Fig. 7 is a plan view of the upper part of a modification of our invention;

Fig. 8 is a front elevation of the complete modified device; and

Fig. 9 is a plan view of the lower part of this modified device.

For purpose of illustration we have chosen a four-stepped cone-pulley 1 properly mounted in a support such as the headstock of a lathe, comprising the base 2 and the

bearing-caps 3 and 4 at the right and left of the pulley respectively, and a similar pulley 5, inversely related to the pulley 1, in a countershaft structure comprising the hangers 6 and 7 depending from an upper support, as the ceiling of a room, some distance to the right and immediately at the left of the cone-pulley 5, respectively. Driving pulleys 8 and 9 are also shown on the countershaft, as usual; it being understood that this structure, so far described, is well known, and is merely an example of many kinds of such mechanism to which our invention is applicable, with such variations as may be needed to conform to the different designs of machines to which it may be applied. The largest step 10 of the lower pulley 1 being at the right, the successively smaller steps 11, 12 and 13 are at the left; and, accordingly, the smallest step 14 of the upper pulley 5 is at the right, with the successively larger steps 15, 16 and 17 at the left. These well known details of cone-pulley arrangement are mentioned merely to facilitate the following description of the application of our invention thereto.

Shortly to the rear and to the right of the smallest upper-pulley step 14 a bracket 18 depends from the ceiling; and some distance out to the left of and to the rear of the left-hand hanger 7 is a similar bracket 19 depending from the ceiling. The two brackets preferably have their tops alined parallel to the counter-shaft, permitting their attachment to a single beam of the ceiling, should this run parallel with the countershaft, as is commonly the case; and the right-hand bracket inclines forwardly downwardly, while the left-hand bracket inclines rearwardly downwardly, to bring the lower parts of these brackets on a line about parallel with a line through the rear corners of the upper-pulley steps. These brackets extend down some distance below the bottoms of the pulley steps, with the front face of the lower part of the right-hand bracket 18 and the rear face of the lower part of the left-hand bracket 19 inclined so as to be normal to the just described line of inclination.

The upper bar 20 is fixed to the inclined faces of the brackets 18 and 19; thus extending substantially horizontally just below the upper pulley, to the rear thereof, and substantially parallel with the pulley-step rear corners. This is a better guidance for the belt-shifting member, in ac-

cordance with our invention, than a guidance merely parallel with the pulley-shaft axis, which results in the belt-shifting member being at more variable distances 5 from the normal line of belt direction on the respective pulley steps. The direction of this bar determines the belt-shifting direction, by which term is meant the line followed by the belt, in general, whether the 10 shifting be to the right or to the left.

The upper rack 21 lies along the front face of the upper bar 20, with teeth projected forwardly for the major part of its length, beginning at the left end; and a U-shaped 15 stirrup 22 straddles the upper bar 20, with its side members projecting forwardly thereof and fixed to the upper and lower edges of the untoothed right-end part of the rack 21, which is of about the same height as the 20 bar 20. This stirrup 22 is the right-hand guide and support for the rack on the bar. Projecting forwardly from the front of this part of the rack 21, and fixed thereto, is the upper belt-stirrup 23, embracing the rear 25 stretch of the belt 24 that runs on the cone pulleys. The upper box 25 embraces the upper bar 20; the upper and lower sides of this box guiding the left-hand end part of the rack 21. The short upper shaft 26 is 30 journaled upright in bearings 27 and 28 in the respective sides of the box 25; and between these sides, enclosed in this box, the upper pinion 29 is fixed on the shaft 26, meshing with the teeth of the rack 21. 35 The lower right-hand bracket 30 is fixed to the top of the front of the right-hand bearing cap 3 of the lower-pulley support, being conveniently attached thereto by the front bolt of the cap, and extends upwardly 40 and forwardly, with a front-to-rear slot 31 in it. A shorter left-hand lower bracket 32 is similarly fixed to the left-hand bearing-cap 4, extending upward the same distance as the right-hand bracket 30, but not so far 45 forwardly; and it is not slotted, but merely has a bolt-hole in its front part. The lower bar 33 has a clip 34 screwed to its back, next to its right-hand end; and this clip 34 has a foot with a bolt through the right-hand 50 bracket slot 31, by which it may be clamped at any desired point along the bracket 30. The lower box 35 is similar to the upper box 25, and similarly straddles the left end part of the lower bar, to the back of which its 55 back is fixed; and it has a foot 36 bolted to the top of the left-hand bracket 32. The lower bar 33 is thus supported just above the lower pulley 1 and just forwardly of it, approximately parallel with a line through the 60 front corners of the steps of the pulley; and this inclination can be adjusted by swinging the bar on its left-hand bracket and clamping it on its right-hand bracket. 65 The lower rack 37 is similar to the upper rack 21 in having teeth projecting forwardly

for the major part of its length, beginning at its left end; and the lower box 35 guides its left end part with the upper and lower sides of the box, which latter have bearings 38 and 39, respectively, for the short lower shaft 40, journaled upright therein, with the lower spur pinion 41 fixed on it between the sides and meshing with the lower rack 37. The connecting-shaft 42 has its upper and lower ends connected to the downwardly extended lower end part of the upper shaft 26 and the upwardly extended upper end part of the lower shaft 40, by the universal joints 43 and 44, respectively; so that the upper and lower mechanisms can be connected with one displaced rearwardly of the other, as is usual in relatively positioning a counter-shaft to a machine. The connecting shaft is preferably made in two sections, connected by a telescopic joint 45, so that it may be lengthened or shortened according to the height of the counter-shaft above the machine and to the amount of rearward displacement of the countershaft. 75 80 85 90 95

The casing 46 is of elongated box-like shape, with the lower bar 33 extending through it from end to end, at the rear; thus supporting and guiding it. The lower rack 37, which is of about the same height as the bar 33 and lies along the front thereof, like the upper rack 21 does along the upper bar 20, extends into this casing through the left end thereof. Fixed to the back of the casing 46, and extending back therefrom, is the lower belt stirrup 47, embracing the front 100 stretch of the belt 24.

The operating head 48 is a rectangular block slidably mounted in the casing 46 next to the front thereof, with a spacer-plate 49 between its rear side and the front side of the rack 37; this spacer-plate being cut away except at the top and bottom, and ends of the casing 46. The front of the casing has a lengthwise slot 50 along the major part of its length, somewhat nearer the left than the right end of the casing; and a handle 51 has a shank extending back through this slot 50 and journaled in the head 48, near the middle thereof, with a bearing-tube 52 tight in the head and projecting forward into the slot 50, so that the handle 51 is well supported for rotation and projects forwardly within easy reach of the operator of the machine. 110 115 120

The right-hand end part of the rack 37 has, close to its lower edge, an extension 53 to the right, with an upstanding barb 54 from the upper edge of which the right-hand end part of the extension 53 is beveled down to the right. 125

The catch-plate 55 comprises a main part 56 of substantially the same front-to-rear thickness as the rack 37 and extending from top to bottom of the casing 46 and fixed thereto, behind the spacer-plate 49, at 130

the right-hand end of the casing 46, with its rear face against the lower bar 33. Extending from the left side of this main part 56 toward the rack 37, is the extension 57, 5 similar to the right-hand extension 53 of the rack 37, with the upstanding barb 58, and with the left end beveled down to the left; being thus presented inversely to the rack extension 53.

10 The shank of the handle 51 has a reduced part 59 extending back nearly to the lower bar 33; and next to the back of the bearing-tube 52 and head 48 it has the lifter 60 pinned on it (Fig. 3) and comprising oppositely extended arms 61 and 62, each with a slight concavity 63 in its upper edge. This lifter prevents displacement of the handle forwardly from the head 48. Behind this lifter 60 two oppositely extending 20 hooks 64 and 65 are pivoted on the extension or reduced part 59 of the handle shank; one having a reduced part which the other straddles, to fit on the part 59, and the right-hand hook 64 having the depending barb 25 66 with its right-hand end beveled up from the lower edge of the barb, while the left-hand hook 65 similarly has the depending barb 67 with its left-hand end beveled up from the lower edge of this barb. A spring 30 68, made of flat resilient metal, is bent in the form of an arch, with opposite ends on the respective hook tops, and with its right-hand end fixed to the top of the hook 64. These hooks 64 and 65 are low enough to 35 leave ample space for this spring 68 above them, under the top of the casing 46; although the spring may strike the casing top as either hook is raised, thus being reinforced in its tendency to keep both hooks 40 down. In the fronts of the hooks 64 and 65 are pins 69 and 70, projecting forwardly, to be engaged by the concavities 63 in the upper edges of the lifter arms 61 and 62, respectively, as the handle is given a partial 45 rotation to the left or to the right.

The rack 37 has a pin 71 fixed in its top near its right-hand end, and the casing 46 has in its top a longitudinal slot 72 extending from near its left end considerably past 50 its middle, with the rack pin 71 therein, to travel from one end to the other thereof. The top 46' of the casing 46 is preferably removable, being held on the lower parts of the casing by screws 73, thus admitting of 55 ready machining of the interior surfaces of the casing, and of the ready assemblage of the parts therein, as well as convenient access thereto at any time for cleaning or repairs. The other parts of the casing 46 60 may be made integral, as shown, including the lower belt stirrup 47. The catch-plate 55 is held in the casing by screws, as the screw 55'.

In the modification shown in Figs. 7 to 9, 65 inclusive, the upper brackets 18' and 19' are

designed to mount the upper bar 20' parallel with the countershaft axis; and the upper rack 21', with the stirrup 22' around the bar 20', has a pair of studs 23' projected forward, with the upper belt-yoke 74 adjustable forwardly and rearwardly thereon to compensate for the angle of shifting of the belt, which is received in the opening 75 in the middle of the yoke 74. The upper and lower boxes 25' and 35' and the connecting shaft 42', joints 43' and 44', and upper and lower pinions 29' and 41' and their shafts 26' and 40' are substantially the same as in the previous example.

The lower bar 33' is mounted on brackets 34' and 36' to hold it parallel with the lower-pulley axis; and the lower rack 37' lies against its face and meshes with the pinion 41' as in the other example. The casing 46' embraces the bar 33' and rack 37'; and on its back has rearwardly projected studs 47', with the lower belt-yoke 76 adjustable forwardly and rearwardly thereon to compensate for the angle of belt shift, with the belt received in its middle opening 77.

The top of the casing 46' has a lengthwise slot 78 in its top, over the rack 37', and a handle 79 is extended through this slot and fastened in the rack. A front handle 80 is fastened in the front of the casing 46' near its right-hand end, projecting forwardly.

With this modified shifter, to shift the belt to the left, the front handle and casing 46' are moved to the left, shifting the lower part of the belt; and then the upper handle 79 and rack 37' are shifted to the left end of the top casing slot 78, the right end of which reached the upper handle 79 during the operation by the front handle 80. This left-hand movement of the lower rack 37' shifts the upper rack 21' to the left, through the medium of the pinions and connecting shaft, completing the shifting. The operation, by alternate use of the handles 79 and 80, is the same in shifting the belt from left to right, except that the upper handle 79 is used first, and then the front handle 80. In any instance, the shifting of the belt any number of steps is a continuous operation for each handle 79 and 80 on pulleys of the usual moderate number of steps, so that there is no establishment of intermediate undesired speeds when shifting from a step to one remote therefrom, and there is no undesirable slackening of the belt during the shifting.

The first example, of Figs. 1 to 6, inclusive, is preferred, because the operator need use only one handle 51, which is hooked, by means of either one of its hooks 64 and 65, to the catch-plate extension 57 for use as the front handle 80 is used in the second example, or to the rack extension 53 for use as the

top handle 79 in the second example. The handle 51, with the operating head 48, may be quickly slid from either end of the casing 46 to the other, releasing its hook 64 or 65 from the extension 57 or 53 by a simple twist of the handle 51 to left or right; and automatically hooking onto either one of these extensions by the beveled hook ends riding up over the bevel-ended extension 10 bars as the handle is forced toward the respective extension. The handle 51 may thus be readily used to move the casing 46, and the lower part of the belt 24 therewith, in either direction; the end of the hook 64 15 abutting the main part of the catch-plate 55 to move the casing to the right. Similarly, the handle 51 may be used to move the rack 37, and through the medium of the connecting mechanism, the upper part of the belt 24, in either direction; the end of the hook 65 abutting the main part of the rack 37 to move the rack to the left. Figs. 4, 5 and 6 show the device when it thus has moved the lower belt end to the left, and is about to 20 begin moving the upper end in the same direction.

In either the first example of Figs. 1 to 6, inclusive, or the second example of Figs. 7, 8 and 9, the projection into the top casing slot, 30 as the pin 71 in the slot 72, or the handle 79 in the slot 78, acts as a gauge to govern the relative movements of the casing and lower belt part, and the rack and upper belt part, and as an indicator to the operator in the 35 alternate use of the two elements. It also, of course, prevents entire escape of the rack from the casing; thus avoiding derangement of the device. The slot is preferably made of length about one and one-half times the 40 width of the steps on the pulleys, permitting ample clearance of the belt leading-end and on-run of the belt following-end.

The device of the second example of Figs. 7, 8 and 9, although requiring the use of two 45 different handles, is simpler, and may be preferred in some cases.

It will be understood that the second example may embody the mountings inclined to the pulley axes and approximately parallel with the pulley-step corners, instead of those exemplified in it; or the mounting may be parallel with the pulley axes in the first example. Or the stirrup construction of either example may be used in the other, either with or without the direction of guiding shown with the respective stirrup constructions; or these stirrups for the belts may be simply elongated to compensate for any discrepancy of direction between the 50 shifter guides and the pulley axes.

All shifting movements, in either example, are accomplished without establishing a driving connection between the pulleys at intermediate undesired steps. The labor of 55 shifting is thus less than where each passed

pair of steps has the belt tightened thereon only to be forced off for the next step toward the desired position; and the wear on the belt and the machine parts, as well as on the shifting device, is less. Also, because the belt at no time during the shifting becomes very slack, it is not exposed to injury, as by dipping its lower end into oil which is frequently found accumulated in a machine below the pulley; and by being kept less slack, the chances of injury to the operator are lessened. The entire device is characterized by an absence of projecting parts and of complicated mechanism; so that it is thus safer, less expensive and more readily kept in order, and does not hinder the work of the machine operator.

Variations other than those exemplified or instanced herein may be desirable in adapting our invention to various machines, or under varying conditions of use, and therefore, while certain constructional details are deemed preferable in connection with our invention, and we have shown and described these rather specifically in elucidating the construction and use of our invention, as is required, we do not wish to be understood as being limited to such precise showing and description, but having thus fully described our invention, what we claim as new and desire to secure by Letters Patent is:

1. In a belt-shifter, two belt-shifting members, means supporting said members and guiding said members in belt-shifting direction, elements operatively connected to the respective members, one element slidably overlapping the other in belt-shifting direction, one element having engaging means spaced apart in belt-shifting direction, and the other element having a projection between said engaging means, a handle slideable on one of said elements in belt-shifting direction, and means whereby said handle may be non-slidably connected to either one of said elements.

2. In a belt-shifter, two belt-shifting members, means supporting said members and guiding said members in belt-shifting direction, a casing operatively connected to one of said members, having a slot extending in belt-shifting direction, an element operatively connected to the other member and slidably extending into said casing parallel with said slot, a projection on said element projecting into said slot, a handle slideable in said casing parallel with said slot, and means whereby said handle may be connected to said element or non-slidably connected to said casing.

3. In a belt-shifter, two belt-shifting members, means supporting said members and guiding said members in belt-shifting direction, elements operatively connected to

70

130

the respective members, one element slidably overlapping the other in belt-shifting direction, a handle slidable on one of said elements in belt-shifting direction, and means whereby said handle may be non-slidably connected to either one of said elements.

4. In a belt-shifter, two belt-shifting members, means supporting said members and guiding said members in belt-shifting direction, a casing operatively connected to one of said members, an element operatively connected to the other member and slidably extending into said casing in belt-shifting direction, a handle, and means whereby said handle may be connected to said element or non-slidably connected to said casing.

5. In a belt-shifter, two belt-shifting members, means supporting said members and guiding said members in belt-shifting direction, elements operatively connected to the respective members, one element slidably overlapping the other in belt-shifting direction, a handle slidable on one of said elements in belt-shifting direction, engaging means on the respective elements, having inversely presented receiving ends, hooks pivoted on said handle and extending toward the respective engaging means to ride on said receiving ends until the hooks retentively engage with the respective engaging means, and means connected to said handle and engaging with said hooks, whereby either one of said hooks may be disengaged from the respective one of said engaging means.

6. In a belt-shifter, two belt-shifting members, means supporting said members and guiding said members in belt-shifting direction, elements operatively connected to the respective members, one element slidably overlapping the other in belt-shifting direction, a handle slidable on one of said elements in belt-shifting direction, engaging means on the respective elements, having inversely presented receiving ends, hooks pivoted on said handle and extending toward the respective engaging means to ride on said receiving ends until the hooks retentively engage with the respective engaging means, means connected to said handle and engaging with said hooks, whereby either one of said hooks may be disengaged from the respective one of said engaging means, and yieldable means engaging with said hooks to hold them in engagement with said engaging means.

7. In a belt-shifter, two belt shifting members, means supporting said members and guiding said members in belt-shifting direction, elements operatively connected to the respective members, one element slidably overlapping the other in belt-shifting direction, a head slidable on one of said elements in belt-shifting direction, a handle rotatable in said head, engaging means on the respec-

tive elements, hooks pivotally mounted on said head to retentively engage with the engaging means of the respective elements, and means rotatable with said handle and engaging with said hooks, whereby either one of said hooks may be disengaged from the respective one of said engaging means.

8. In a belt-shifter, two belt-shifting members, means supporting said members and guiding said members in belt-shifting direction, a casing operatively connected to one of said members, having a slot extending in belt-shifting direction, a rack slidably extending into said casing parallel with said slot, a projection on said rack projecting into said slot, a handle slidable in said casing parallel with said slot, means whereby said handle may be connected to said rack or non-slidably connected to said casing, a rack operatively connected to the other one of said members, a shaft, and pinions fixed on said shaft and meshing with respective ones of said racks.

9. In a belt-shifter, two belt-shifting members, means supporting said members and guiding said members in belt-shifting direction, a casing operatively connected to one of said members, a rack slidably extending into said casing in belt-shifting direction, a handle slidable in said casing in belt-shifting direction, means whereby said handle may be connected to said rack or non-slidably connected to said casing, a rack operatively connected to the other one of said members, a shaft, and pinions fixed on said shaft and meshing with respective ones of said racks.

10. In a belt-shifter, two belt-shifting members, means supporting said members and guiding said members in belt-shifting direction, a casing operatively connected to one of said members, a rack slidably extending into said casing in belt-shifting direction, means for alternatively applying manual effort to said casing or said rack directly in belt-shifting direction, a rack operatively connected to the other one of said members, a shaft, and pinions fixed on said shaft and meshing with respective ones of said racks.

11. In a belt-shifter, two belt-shifting members, means supporting said members and guiding said members in belt-shifting direction, a casing operatively connected to one of said members, having a slot extending in belt-shifting direction, a rack slidably extending into said casing parallel with said slot, a projection on said rack projecting into said slot, means for alternatively applying manual effort to said casing or said rack directly in belt-shifting direction, a rack operatively connected to the other one of said members, a shaft, and pinions fixed on said shaft and meshing with respective ones of said racks.

12. In a belt-shifter, two belt-shifting

- members, means supporting said members and guiding said members in belt-shifting direction, elements operatively connected to the respective members, one element slidably overlapping the other in belt-shifting direction, one element having engaging means spaced apart in belt-shifting direction a distance materially greater than the width of any steps on cone-pulleys with which said shifter is to be used, and the other element having a projection between said engaging means, and means for alternatively applying manual effort to said elements directly in belt-shifting direction.
15. 13. In a belt-shifter, two belt-shifting mechanisms, a single handle, and means to connect said handle to either one of said mechanisms, for alternatively applying manual operative effort to said mechanisms directly in shifting direction.
16. 14. In combination with mated stepped pulleys and a belt to run on different pairs of steps of said pulleys, a shifter comprising members engaging said belt near the respective pulleys, means for alternatively applying manual operative effort to said members directly in belt-shifting direction, and means whereby each one of said members moves the other member in shifting direction after a shifting movement through a distance materially greater than the width of any step of said pulleys and independently of said other member.
17. In combination with mated stepped pulleys and a belt to run on different pairs of steps of said pulleys, a shifter comprising means for first advancing said belt from a larger step of one pulley materially beyond a smaller step on said pulley, and then upon continued operation in the same direction advancing said belt from a smaller to a larger step on the other pulley, repeatedly, and means for further advancing said belt on said other pulley when the limit of movement of the first mentioned means has been reached.

GEORGE J. HAUSMAN.
